UNITED STATES PATENT OFFICE.

JOSEPH J. WALSER, OF ANN ARBOR, MICHIGAN, ASSIGNOR TO GOSS PRINTING PRESS COMPANY, A CORPORATION OF ILLINOIS.

PRINTING-PRESS.

1,388,676.

Specification of Letters Patent. Patented Aug. 23, 1921.

Application filed March 12, 1920. Serial No. 365,283.

To all whom it may concern:

Be it known that I, JOSEPH J. WALSER, a citizen of the United States, residing at Ann Arbor, in the county of Washtenaw and State of Michigan, have invented certain new and useful Improvements in Printing-Presses, of which the following is a specification.

The invention relates to printing presses and more particularly to fast rotary perfecting presses, such as are used for newspaper work and in its principal aspects the invention relates to late news or "fudge" devices as such, and as coöperating with the other mechanisms of the press, and more particularly to late news devices adapted to be a part of, and to coöperate with, the other mechanisms of fast rotary newspaper presses.

Objects and advantages of the invention will be set forth in part hereinafter and in part will be obvious herefrom or may be learned by practice with the invention; the same being realized and attained through and by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is an elevation, partly diagrammatic, of a printing press and folder embodying the invention;

Fig. 2 is a fragmentary elevation of the same general character as Fig. 1, showing the upper central part of Fig. 1, but on an enlarged scale, and showing the late news device printing on one side of the web; and

Fig. 3 is a view similar to Fig. 2 and showing the late news device printing on the opposite side of the web;

Fig. 4 is a fragmentary detail in elevation of the direction reversing device of the cylinders of the late news mechanism; and

Fig. 5 is a fragmentary transverse elevation of the same parts as are shown in Fig. 4.

In newspaper work it is frequently necessary to print late news or other extra matter

not carried on the regular plates, and it is desirable, and it is necessary frequently to print late news and "extras" without making new plates. It is also deemed advantageous by certain newspapers to print certain news or announcements in some color other than the black used for the printing of the body of the newspaper. All such devices are usually termed late news or "fudge" devices.

Objects of the present invention are to provide a late news device which is capacitated to print alternatively or selectively upon either side of the web which is running through the printing couples of a fast rotary perfecting press; to provide such a mechanism which is independent of the cylinders of the regular printing couple, that is the plate and impression cylinders employed in printing the body of the newspaper on both sides of the web; to provide such a mechanism capable of being selectively positioned transversely of the press and of the web to print in any desired position transversely of the web with respect to the pages and columns printed on the web by the regular printing couples of the press; to provide a late news mechanism reversible in its direction of rotation to run the web through in either direction; to provide such a mechanism capacitated to operate in different sequential relation to the regular printing cylinders or printing couples of the press. Other objects and advantages of the invention will be pointed out later herein.

The invention broadly, as embodied, comprises a late news device having its own form cylinder and coöperating impression cylinder, with an inking mechanism for the form cylinder adapted to give adequate and acceptable inking service. The late news device of this character is located relatively to, and correlated with respect to, the two coöperating printing couples or sets of cylinders which print the running web upon both sides, or "perfect" it, and with respect to the paper supply so that the late news or like supplemental matter may be printed by the late news device upon either side of the running web. More particularly as to the embodied form, the cylinders of the late news device are rotatable alternatively or selectively in either direction, so that either side of the web may be presented thereto to receive the late news imprint. More particu-

larly, the late news device is additionally located and correlated with respect to the web supply and the printing couples so that the web, in connection with the reversibility 5 of rotation of the cylinders of the late news device, may be led as desired primarily either to the late news device or to the first regular printing couple and from either of these to the second or perfecting printing 10 couple.

Referring first to the details of construction of the general press mechanism, in so far as they are applicable or necessary to illustrate and elucidate the relation to and 15 the coöperation therewith of my improved late news device, a three deck rotary perfecting fast newspaper press is shown running to a folder, which folder may be centrally located with a similar printing mechanism upon the opposite side thereof. Such a press as shown is capacitated to perfect three webs, to slit and associate them, and to fold them so associated, the late news device of each deck being capacitated to print 20 upon any page and upon either side of the web, and thus upon either side of any page of the web. The slitting, associating and folding mechanisms serve to bring various late news imprints into any desired relation with each other as well as with the other matter in the paper printed by the 25 regular pairs of cylinders.

In the illustrated form, comprising essentially by way of exemplification the various 30 features above outlined, the lowermost deck of the press comprises a first form cylinder 1 and a coöperating impression cylinder 2. The form cylinder 1 is provided with inking mechanism for inking the plates thereon, 35 said inking mechanism comprising a series of form rollers 3, an ink drum 4, an auxiliary ink drum 5, an ink fountain 6, a fountain roller 7 and a ductor roller 8, the latter vibrating between the fountain roller 7 and the 40 ink drum 5, together with other auxiliary rollers which need not be described in detail. The web α , which may be derived from any one of a plurality of sources, such as a web roll 9 or a web roll 10, is run between 45 the cylinders 1 and 2 and printed thereby upon one side in the usual manner.

The second printing couple for the web α comprises a form cylinder 11 having an inking mechanism 12, which may be the same 50 as that of the cylinder 1 and need not be described in detail. Coöoperating with the form cylinder 11 is an impression cylinder 13, the web α passing therebetween and being printed upon the second side or "perfected" 55 in a well-known manner. If it is desired to print the web α upon one side only, it may be guided past the cylinders 11, 13 of the second printing couple without passing therethrough or being printed upon there-

by, guiding rollers 14 being located to guide 60 web α from the cylinder 2 directly to the associating and folding mechanism. The web α is shown going direct from the second printing couple over a roller 15 to a longitudinal folder or former 16 which may be 65 either the first or the sole folding device of the folding mechanism 17. There is usually in such devices also a transverse folder and a delivery.

At 18 is shown a set of turning bars where- 70 by the web α , after being slit by a longitudinal slitter, has its halves superposed or associated as at α^2 , and then run over the roller 15 and into the folder as already de- 75 scribed.

The late news device for the first web is indicated by reference numeral 19, and the details of construction and operation there- 80 of, as embodied, will be set forth at a later point as applicable to the late news devices 85 of all the decks.

Referring now briefly to the second deck, a first form cylinder 25 is provided with inking mechanism 26 and a coöperating impres- 90 sion cylinder 27. The second printing couple of this deck has a form cylinder 28, inking mechanism 29 therefor, and a coöperating impression cylinder 30. The web 95 γ is derivable from a plurality of sources, such as web rolls 31 or 32, suitably located, the web passing between form cylinder 25 and impression cylinder 27 to be printed upon one side and passing thence to the form cylinder 28 and impression cylinder 30 to be printed upon the opposite side. The 100 by-pass rolls 14, already described in connec- 105 tion with the first deck, may be employed on one side by the first printing couple. A set of turning bars marked 18 are shown, and the previous description may be applied thereto.

The late news device for the second deck of the press is indicated by 33, and the general description of this mechanism in de- 110 tail, which will be given later, is applicable to this mechanism.

The present embodiment shows a three deck press, the top deck having a first printing couple with a form cylinder 36, having 115 inking mechanism 37, and an impression cylinder 38. The second printing couple is shown with an impression cylinder 39, hav- 120 ing an inking mechanism 40, and a coöperating impression cylinder 41. The web γ , derivable from a plurality of sources of supply, such as the web rolls 42 or 43, is printed upon by the first printing couple upon one side and by the second printing couple upon the opposite side. The rollers 14 and fold- 125 ing bars 18 are shown for the web γ , and the description already given may be applied thereto.

The web z^3 is shown directed to a second or central folder as 45, and being associated at roller 44 with a web m from the other side of the press (not shown), the webs being 5 associated at 44 and folded together at 45. The late news device for the printing couples of this deck is indicated generally by 46, and may conform to the general description to be given later.

- 10 Referring now to the late news device, as embodied, it is provided with a form cylinder 50, having a suitable inking mechanism 51, shown as comprising form rollers 52 and 53, an ink drum 54, an ink fountain 55 and 15 a fountain roller 56. Coöperating with the form cylinder 50 is an impression cylinder 57, the web passing therebetween, and presenting either side thereto, as will be later described, to receive this additional printing 20 of the late news device selectively or alternatively on either side of the web.

Means are provided for rotating the cylinders 50 and 57 in either direction in connection with the present embodiment of 25 means for printing the supplementary matter from the late news device upon either side of the web. This will be described, in detail in connection with the means for driving or rotating the cylinders of the late news 30 device so as to run the web in either direction therethrough.

Referring now to the matter of running the press to cause the late news device to print alternatively or selectively upon either 35 side of the web, in Figs. 2 and 3 the letter a is applied to the side of the web z which is printed upon by the first printing couple, and the letter b to the other side of the web z which is printed upon by the second printing 40 couple.

In Fig. 2 the web z is shown directed primarily between the cylinders 36 and 38 of the first couple and thence between the cylinders 50 and 57 of the late news device, the 45 cylinder 50 rotating in Fig. 2 in counter clockwise direction and cylinder 57 rotating in clockwise direction. The supplementary or late news matter in such case is printed upon the side b of the web z . The 50 web then passes between form cylinder 39 and impression cylinder 41, and receives the regular printing matter for the side b , thereby perfecting the web.

In Fig. 3 the arrangement is shown wherein 55 the late news device prints upon the side a of the web. In the arrangement of Fig. 3 the web z is led primarily through the late news device before going to the first printing couple, the form cylinder 50 in Fig. 3 rotating in clockwise direction and the impression cylinder 57 rotating in counter clockwise direction. The supplementary or late news matter is thus printed upon the side a of the web z .

The web* in this case proceeds or passes 65 from the late news device 46 to the cylinders 36 and 38 of the first printing couple, which prints the regular matter on the side a of the web, and passes thence through cylinders 39 and 41 to perfect the web, that is to print 70 the regular matter on the side b .

The embodied form of means for reversing the direction of rotation of the cylinders 57 and 50 comprises a gear wheel 60 which is driven in one direction by any suitable 75 connection, such as one or more intermediate or idler gears (not shown) from the usual press drive. Gear wheel 60 is journaled on a stub shaft 61 supported on the press frame.

Pivoted on shaft 61 is a plate 62 in which 80 is journaled at one side a gear wheel 63, which meshes with gear wheel 60. Journaled in plate 62 at the opposite side is a gear wheel 64 also in mesh with gear wheel 60. Also journaled in plate 62 is a gear 85 wheel 65, which is in mesh with gear wheel 64. Thus, gear wheels 63 and 65 are both driven from gear wheel 60, but rotate in opposite directions.

The gear wheels 63 and 65 are brought 90 alternatively into mesh with a gear wheel 66 fixed on shaft 67 of cylinder 57 of the late news device. The cylinder 57 is accordingly rotated in one direction or the other, to coöperate with the regular printing 95 couples, to print the late news selectively or alternatively on either side of the web as already described. Meshing with gear wheel 66 is a gear wheel 68, which is fixed on shaft 69 of cylinder 50 of the late news 100 device. Thus cylinders 57 and 50 rotate together in the usual manner of a rotary printing couple.

In the embodied form of mechanism for reversing the direction of rotation, the plate 105 62, due to its pivotal mounting on stub shaft 61, rocks to bring either gear wheel 63 or gear wheel 65 into mesh with gear wheel 66. The plate 62 is shown in intermediate 110 position in Fig. 4. For the purpose of holding plate 62 in either position, a slot 70 is formed therein, through which passes a bolt 71, screw-threaded into the machine frame.

The manner of operation of the mechanism has been fully set forth in connection 115 with the description of the various groups of mechanisms, or will be obvious without further detailed statement.

The invention in its broader aspects is not limited to the specific mechanisms shown 120 and described but departures may be made therefrom within the scope of the accompanying claims without departing from the principles of the invention and without sacrificing its chief advantages.

What I claim is:—

1. A printing press including in combination a rotary printing couple printing one

1
side of a web, a rotary couple printing the other side of the web, and a rotary late news device separate from but located adjacent to the printing couple, and means directing the web alternatively primarily to the printing couple or to the late news device to cause the late news device to selectively print upon one side or the other of the web.

2. A printing press including in combination a rotary printing couple printing one side of a web, a rotary couple printing the other side of the web, a late news device comprising a form cylinder and a coöperating impression cylinder and inking mechanism, separate from but located adjacent to the printing couple, and means directing the web alternatively primarily to the printing couple or to the late news device to cause the late news device to selectively print upon one side or the other of the web.

3. A printing press including in combination a rotary printing couple, a late news device comprising a form cylinder and impression cylinder, means for changing the direction of rotation of the late news device, and means for directing the web selectively in opposite directions through the late news device to cause it to print alternatively on either side of the web and to direct the web selectively either first through the printing couple or through the late news device.

4. A printing press including in combination a rotary printing couple printing one side of a web, a rotary couple printing the other side of the web, a rotary late news device separate from but located adjacent to the printing couples, and means directing the web alternatively primarily to one or the other of said mechanisms and alternatively in opposite directions to the late news device to cause the late news device to selectively print upon one side or the other of the web.

5. A printing press including in combination a rotary printing couple printing one side of a web, a rotary couple printing the other side of the web, a late news device comprising a form cylinder and a coöperating impression cylinder separate from but located adjacent to the printing couples, and means directing the web alternatively primarily to one or the other of said mechanisms and alternatively in opposite direc-

tions to the late news device to cause the late news device to selectively print upon one side or the other of the web.

6. A printing press including in combination a first printing couple printing one side of the web, a second printing couple printing the other side of the web, a rotary late news device comprising a form cylinder and a coöperating impression cylinder separate from but located adjacent to the printing couples, and means for directing the web primarily to either the first couple or the late news device and then to the other of them and then to the second printing couple to cause the late news device to print selectively on one side or the other of the web.

7. A printing press including in combination a first printing couple printing one side of the web, a second printing couple printing the other side of the web, a late news device located adjacent to and between the printing couples, and means for directing the web primarily to either the first couple or to the late news device and then to the other of them and through the late news device selectively in either direction and then to the second printing couple to cause the late news device to print selectively on one side or the other of the web.

8. A printing press including in combination a first printing couple printing one side of the web, a second printing couple printing the other side of the web, a rotary late news device comprising a form cylinder and a coöperating impression cylinder located adjacent to and between the printing couples, and means for directing the web primarily to either the first couple or to the late news device and then to the other of them and through the late news device selectively in either direction and then to the second printing couple to cause the late news device to print selectively on one side or the other of the web.

In testimony whereof, I have signed my name to this specification, in the presence of two subscribing witnesses.

JOSEPH J. WALSER.
